FRANKLIN BERTRAND WARRING, OF SAN JOSE, CALIFORNIA, ASSIGNOR TO BEAN SPEAY PUMP CO., OF SAN JOSE, CALIFORNIA, A CORPORATION OF CALIFORNIA.

DEEP-WELL PUMP.

1,139,607.

Specification of Letters Patent.

Patented May 18, 1915.

Application filed April 15, 1914. Serial No. 831,995.

To all whom it may concern:

Be it known that I, FRANKLIN BERTRAND WARRING, a citizen of the United States, residing at San Jose, in the county of Santa

5 Clara and State of California, have invented certain new and useful Improvements in Deep-Well Pumps, of which the following is a specification.

My invention relates to that class of deep-well pumps, in which a centrifugal, turbine or similar type of pump is located in the well or pit and is driven by a line-shaft which is parallel with but exterior to the discharge pipe of the pump. In this class 10 of pumps, the line-shaft, which is usually of great length, has to be supported at proper intervals by suitable bearings, and these bearings must themselves be supported and they must be lubricated.

20 It is the object of my invention to secure these results by simple and effective means, and to this end my invention consists in line-shaft bearings supported directly by the discharge pipe, and in the novel constructions and connections of said bearings for lubricating them, all as I shall now 25 fully describe by reference to the accompanying drawings, in which—

Figure 1^a and Fig. 1^b show a vertical section, broken, of my pump. Fig. 2 is a cross section, enlarged, on the line x—x of Fig. 1^b. Fig. 3 is a cross section, enlarged, on the line y—y of Fig. 1^a. Fig. 4 is a cross sectional view showing two discharge pipes 30 and a form of supporting clamps adapted for this construction.

1 is a pulley through which power is applied to the vertical line shaft 2 mounted in bearings 3 and 4, located in the frame 5 and the discharge elbow 6 respectively.

7 is the well-casing.

The vertical line shaft 2 communicates power from the pulley 1 to the impeller or impellers 8 contained in the pump body 9, located within the well casing 7.

Attached to the pump body 9 is a three port discharge manifold 10 designed to deliver the water discharged from the pump into the discharge pipe or pipes, of which 50 three are shown here, designated by 11. More or less than three discharge pipes may be employed for the above service without affecting the spirit of this invention; thus in Fig. 3 I have shown three, while in Fig. 55 4 I have shown two discharge pipes. The

former construction is adapted for a small or circular well, while the latter construction is best for a larger or rectangular well or pit.

Located at intervals, say, every five feet, 60 more or less, along the length of vertical line shaft 2 are bearings, the bodies of which are indicated by 12. The bearing bodies 12 are provided with oil receiving-chambers 13 and oil discharge-chambers 14. These two 65 chambers are connected by vertical passages 15 which permit the overflow and the passage by gravity of the oil from the receiving chambers 13 to discharge chambers 14. In the form of supports for the bearings, 70 shown in connection with the three discharge pipes, the bearing bodies 12 are provided with tapped holes to receive studs or bolts 16, which studs or bolts by means of nuts 16' are used to tighten the clamps 17 75 upon the vertical discharge pipes 11, and to draw said discharge pipes firmly against said bearing bodies 12, whereby said bodies are supported by said pipes. A recess or oil pocket 18 is provided in each oil receiving 80 chamber 13 for the accumulation of sufficient oil for lubricating the journals on vertical line shaft 2. Oil pipes 19 conduct the surplus oil from the discharge chamber 14 of each bearing to the receiving chamber 13 of the next bearing below. Oil which 85 leaks by each journal is thrown outward by the revolving oil collar 20 and is caught in the discharge chamber 14, being prevented from leaking past shaft 2 by the raised annular rim 21. The set collar or sand-cap 22 is to prevent the entrance of sand and dirt to the bearing body 12.

23 is an oil supply tank for feeding oil into the oil box 24 located just over the discharge elbow bearing 4 at the top of the well. From this box a pipe 24' leads the oil to the receiving chamber 13 of the first bearing 12. While oil is mentioned as the lubricant for the bearings above the water line in the well, it may be convenient and practical at times to run water through pipes 19 as a substitute for oil.

The pulley frame bearing 3 is provided with a ball or other suitable type of thrust bearing 25 for taking any unbalanced vertical thrust during the operation of the pump.

A discharge flange 26 carrying the discharge elbow 6 is provided to cover the top 110

of the well and to support the vertical discharge pipes 11, which pipes in turn support and hold in alinement the bearings 12, and support the pump at their lower ends. The 5 discharge pipes 11 are fastened to said discharge flange 26 by means of nuts 27 which are screwed to give the required adjustment.

It will be observed that the arrangement described provides for great compactness, 10 thereby allowing the pump to be lowered into a well of small cross sectional area. It is of comparatively cheap construction, and the bearings can be readily inspected by raising the pump from the well. Those 15 bearings which happen to be submerged will be water lubricated, while those above the level of the water in the well, will be lubricated with oil from the supply coming from the receptacle next above.

20 In Fig. 4, I show a form of support for the bearings, adapted for two discharge pipes. The bearings and pipes are here designated by the same numerals as in the other figures. The clamps 28 in this case 25 consist of a pair of opposing members properly embracing the pipes and bearings and held by bolts 29.

I claim:—

1. In a deep-well pump of the described 30 class, the combination of a pump; a plurality of discharge pipes connected with and supporting said pump; a discharge member fixed at the well mouth, said member being common to and suspending all of said discharge pipes; and provided with a central bearing; a pump-operating line-shaft mounted in the central bearing of the discharge member; other bearings for the line-shaft at intervals within the well; and means 35 for supporting said other bearings from the discharge-pipes.

2. In a deep-well pump of the described 40 class, the combination of a pump; a plurality of discharge pipes connected with and supporting said pump; a fixed flange at and covering the well-mouth, the discharge-pipes being suspended from said flange and said flange having a central bearing; a discharge elbow carried by the fixed flange, said elbow 45 communicating with all of the discharge pipes and provided with a central bearing; a pump-operating line-shaft mounted in the central bearings of the flange and discharge elbow; other bearings for the line-shaft at 50 intervals within the well; and means for supporting said other bearings from the discharge-pipes.

3. In a deep-well pump of the described 55 class, the combination of a pump; a plurality of symmetrically disposed discharge pipes connected with and supporting said pump; a discharge member fixed at the well mouth, said member being common to and suspending all of said discharge pipes, and 60 provided with a central bearing; a pump-

operating line-shaft mounted in the central bearing of the discharge member and thence extending in the axis of said plurality of discharge pipes; other bearings for the line-shaft at intervals within the well; and means 70 for supporting said other bearings from the discharge-pipes, comprising symmetrically disposed clamps, each bearing upon a pair of adjacent discharge pipes, bolts connected with and extending from the bearings outwardly between adjacent discharge pipes and passing through the clamps, and nuts on the outer ends of the bolts to set the clamps up to the discharge pipes and to draw the bearings to and against said pipes. 75

4. In a deep-well pump of the described class, the combination of a pump; a plurality of discharge pipes connected with and supporting said pump; a fixed flange at and covering the well-mouth, the discharge pipes 80 passing upwardly through said flange and suspended therefrom by nuts on their upper ends and said flange having a central bearing; a discharge elbow resting upon and bolted to the fixed flange, said elbow communicating with all the discharge pipes and provided with a central bearing; a pump-operating line-shaft mounted in the central 85 bearings of the flange and discharge elbow; other bearings for the line-shaft at intervals within the well; and means for supporting said other bearings from the discharge-pipes. 90

5. In a deep-well pump of the described 95 class, the combination of a pump; a discharge pipe from said pump; a pump-operating line-shaft parallel with and exterior to said discharge pipe; bearings at intervals along the length of the line shaft in which said shaft is journaled, each of said bearings having an upper chamber open to the shaft journal, and a lower chamber also open to said journal, said chambers having a communicating passage; a pipe to supply a lubricant to the upper chamber of the first 100 bearing; and a pipe connecting the lower chamber of each bearing with the upper chamber of the next lower bearing. 110

6. In a deep-well pump of the described 115 class, the combination of a pump; a discharge pipe from said pump; a pump-operating line-shaft parallel with and exterior to said discharge pipe; bearings at intervals along the length of the line shaft in which said shaft is journaled, each of said bearings having an upper chamber open to the shaft journal, with a pocket at the entrance to said journal, and a lower chamber also open to said journal, said chambers having a communicating passage; a pipe to supply a lubricant to the upper chamber of the first bearing; and a pipe connecting the lower chamber of each bearing with the upper chamber of the next lower bearing. 120

7. In a deep-well pump of the described 125 class,

- class, the combination of a pump; a discharge pipe from said pump; a pump-operating line-shaft parallel with and exterior to said discharge pipe; bearings at intervals 5 along the length of the line shaft in which said shaft is journaled, each of said bearings having an upper chamber open to the shaft journal, and a lower chamber also open to said journal, and provided with a raised 10 annular rim in its bottom about the shaft, said chambers having a communicating passage; a pipe to supply a lubricant to the upper chamber of the first bearing; and a pipe connecting the lower chamber of each 15 bearing with the upper chamber of the next lower bearing.
8. In a deep-well pump of the described class, the combination of a pump; a discharge pipe from said pump; a pump-operating line-shaft parallel with and exterior to said discharge pipe; bearings at intervals 20 along the length of the line shaft in which said shaft is journaled, each of said bearings having an upper chamber open to the shaft journal, and a lower chamber also open to said journal, said chambers having a communicating passage; a pipe to supply a lubricant to the upper chamber of the first 25 bearing; a pipe connecting the lower chamber of each bearing with the upper chamber of the next lower bearing; and means for supporting the bearings from the discharge pipe. 70
9. In a deep-well pump of the described class, the combination of a pump; a discharge pipe from said pump; a pump-operating line-shaft parallel with and exterior to said discharge pipe; bearings at intervals 30 along the length of the line shaft in which said shaft is journaled, each of said bearings having an upper chamber open to the shaft journal, and a lower chamber also open to said journal, and provided with a raised 35 annular rim in its bottom about the shaft, said shaft having a collar just above said rim, and said chambers having a communicating passage; a pipe to supply a lubricant to the upper chamber of the first bearing; and a pipe connecting the lower chamber of each bearing with the upper chamber of the next lower bearing.
35. 9. In a deep-well pump of the described class, the combination of a pump; a discharge pipe from said pump; a pump-operating line-shaft parallel with and exterior to said discharge pipe; bearings at intervals 40 along the length of the line shaft in which said shaft is journaled, each of said bearings having an upper chamber open to the shaft journal, with a pocket at the entrance to said journal, and a lower chamber also 45 open to said journal, and provided with a raised annular rim in its bottom about the shaft, said shaft having a collar just above
- said rim, and said chambers having a communicating passage; a pipe to supply a lubricant to the upper chamber of the first 50 bearing; and a pipe connecting the lower chamber of each bearing with the upper chamber of the next lower bearing.
10. In a deep-well pump of the described class, the combination of a pump; a discharge pipe from said pump; a pump-operating line-shaft parallel with and exterior to said discharge pipe; bearings at intervals 55 along the length of the line shaft in which said shaft is journaled, each of said bearings having an upper chamber open to the shaft journal, and a lower chamber also open to said journal, said chambers having a communicating passage; a pipe to supply a lubricant to the upper chamber of the first 60 bearing; a pipe connecting the lower chamber of each bearing with the upper chamber of the next lower bearing; and means for supporting the bearings from the discharge pipe. 75
11. In a deep-well pump of the described class, the combination of a pump; a discharge pipe from said pump; a pump-operating line-shaft parallel with and exterior to said discharge pipe; bearings at intervals 75 along the length of the line shaft in which said shaft is journaled, each of said bearings having an upper chamber open to the shaft journal, and a lower chamber also open to said journal, said chambers having a communicating passage; a pipe to supply a lubricant to the upper chamber of the first bearing; a pipe connecting the lower chamber of each bearing with the upper chamber of the next lower bearing; and clamps for 80 binding the discharge pipe and the bearings together. 85

In testimony whereof I have signed my name to this specification in the presence of two subscribing witnesses.
